UNITED STATES PATENT OFFICE.

JOHN W. PRIDMORE, OF CHICAGO, ILLINOIS, ASSIGNOR TO INTERNATIONAL HARVESTER COMPANY, OF CHICAGO, ILLINOIS, A CORPORATION OF NEW JERSEY.

SPRING-CLIP FOR THE CUTTING APPARATUS OF MOWERS, REAPERS, &c.

SPECIFICATION forming part of Letters Patent No. 731,611, dated June 23, 1903.

Application filed September 24, 1902. Serial No. 124,632. (No model.)

To all whom it may concern:

Be it known that I, JOHN W. PRIDMORE, a citizen of the United States, and a resident of Chicago, Cook county, Illinois, have invented 5 certain new and useful Improvements in Spring-Clips for the Cutting Apparatus of Mowers, Reapers, &c.; and I do hereby declare the following to be a full, clear, and exact description of the invention, such as will 10 enable others skilled in the art to which it app pertains to make and use the same.

The invention relates to the clips that are commonly employed for holding the cutters of mowers, reapers, and the like in working 15 contact with the ledger-plates on the guard-fingers, and it has to do more particularly with spring-clips, by means of which the cutters are held elastically down on the guards.

In the present improvement the clip comprises a plate-like finger, which does not move horizontally with the cutters, but is arranged to fulcrum on the finger-bar in a vertical plane, and is provided with a spring, by 20 means of which its forward end is held down- 25 wardly on the cutters. The finger is housed and protected by a cap that is secured to the finger-bar, and the finger may be fulcrumed directly on the bar or indirectly thereon through the intermediary of the cap. Two 30 constructions are illustrated herein. In one of these constructions the fulcrum is on the front edge of the cap, about midway of the length of the finger, and the spring is located behind the fulcrum and reacts between the 35 finger-bar and the under side of the rear end of the finger. In the other construction the fulcrum is directly on the finger-bar at the rear end of the clip-finger, and the spring is located in front of it. The reaction of the 40 spring in the latter case is between the upper side of the clip-finger and the cap, and in the first-described construction it is between the under side of the clip-finger and the finger-bar, as above described; but the reaction in 45 both cases is really between the finger-bar and the clip-finger, the cap being to all intents and purposes a part of the bar.

The invention is illustrated in the accompanying drawings, forming a part of this 50 specification, wherein—

Figure 1 is a perspective view of a part of a cutting apparatus, showing my clip in place. Fig. 2 is a vertical cross-section on the line 2 2 of Fig. 1. Fig. 3 is a perspective view of the clip-finger detached. Fig. 4 shows a 55 modified construction of the clip in perspective. Fig. 5 is a vertical cross-section of this form on the line 5 5, Fig. 4. Fig. 6 is a detailed perspective of the form of finger shown in Figs. 4 and 5. 60

Referring to the views, *a* denotes the finger-bar; *b*, the guard-fingers; *c*, the cutter-bar, and *d* the cutters or knife-sections. These parts, together with the wear-plate *e*, are of the usual construction and arrangement. 65

The clip comprises a plate-like finger *f* and a housing or cap *g*. The finger is made broad and flat at its end to provide ample wearing-surface and so that it will overlap the adjacent edges of the cutter-sections at the V-shaped spaces between them. The cap is secured to the finger-bar by bolts *g'*, passing through ears or wings *h*, projecting from its opposite ends. The front ends of these wings project over the rear edge of the cutters, as 75 shown at *h'*, and prevent the rear edges of the cutters from leaving their bearing on the plate *e*. The cap is of a generally box-like form and constitutes a housing for and means of securing the clip-finger to the finger-bar. 80 It is provided on its upper side with a dome-shaped projection *i*, the purpose of which will be described later on, and the end of the cap is open at the front, so as to permit the clip-finger to project beyond it and over well 85 forward onto the cutter-sections.

As shown in Figs. 1, 2, and 3, the cap is provided with a turned-down lip or edge *l* at its front side, and the clip-finger *f* is formed with a transverse groove or depression *j*, so 90 that the finger fits snugly between the lower edge of the lip of the cap and the wear-plate *e*. The lip *l* therefore forms a fulcrum upon which the clip-finger may rock slightly. Moreover, it closes the front end of the cap 95 and prevents the entrance of dust, dirt, &c. The rear end of the clip-finger is provided with a cup-shaped recess *k*, and a coil-spring *k'*, which is seated on a button *l*, set loosely on the wear-plate, is loosely inclosed and con- 100

fined by said recess. The wings h of the cap have vertical flanges h^2 projecting forwardly and upwardly at the sides of the turned-down edge l' , the object being to prevent sidewise movement of the clip-finger and to give additional wearing-surface for the edges of the finger as the cutter-bar reciprocates instead of allowing the sides of the cap to resist the tendency to lateral movement of the finger, caused by the reciprocation of the cutters. The dome-like formation i on the upper side of the housing or cap g is provided for the purpose of receiving the cup-shaped projection k on the rear end of the clip-finger.

15 Referring now to Figs. 4, 5, and 6, the finger-bar a , the guard-finger b , the cutter-bar c , the cutters d , and the wear-plate e are of precisely the same construction as in the first three figures. The clip, however, is modified to the extent of locating the fulcrum j' at the rear end of the finger and directly on the bar a instead of on the cap or housing about midway of the ends of the finger, as in the construction first described. The housing or cap g' has a dome i'' near its front edge instead of at the rear, as in the first-described construction, and the spring k^2 , which is inclosed in the dome, bears downwardly upon the clip-finger f' at a point forward of its fulcrum instead of in the rear thereof, as shown in Fig. 2. In either case the action of the spring is to hold the front end of the clip-finger down upon the cutters, and the only difference in the two forms is the constructional one of changing the clip-finger from a lever of one order to that of another.

The object of the broad flat bearing-surface f^3 has been already described, and both forms of the finger are preferably arched, as shown in all the figures, to provide a free passage-way for the rivets, by means of which the cutters are secured to the cutter-bar.

It is desirable in both constructions to provide some means for positively preventing the finger from working forwardly out from under the cap. In the construction shown in Fig. 2 the depending front edge l' , which forms the fulcrum for the finger, performs this office in connection with the shoulder j^2 on the finger in rear of the transverse groove j . In the construction shown in Fig. 5 a bar l^3 , extending across the cap from side to side, coöperates with the downwardly-projecting fulcrum j' and performs the same office. The rear edge of the wear-plate e or any other projection on the finger-bar would do the same thing. The spring k^2 in the construction shown in Fig. 5 also incloses an acorn-shaped button l^4 , which like the other projects within the coils of the spring and has a flanged head upon which the lower coil of

the spring rests, the object being to keep the spring upright and prevent it from tilting and becoming otherwise disarranged.

The construction being as thus described, it will be noted that the cutters are held elastically down on the guard-fingers by means of a clip-finger which does not oscillate as the cutter-bar reciprocates, also that the finger is rigid and unyielding and derives its elasticity from the spring that is inclosed by the dome-like projection of the housing. The finger is not connected to the cap or the finger-bar by pivot-pins or hinges, but is loosely fulcrumed, as above described, and held down in working position by the housing or cap, so that on removal of the latter the finger is free to be disengaged from both the cutters and the finger-bar.

Having thus described my invention, what I claim is—

1. The combination with the finger-bar and cutters of mowers, reapers and the like, of a spring-clip comprising a cap or housing, a finger fulcrumed on the finger-bar and partly covered by the cap, and a spring holding the front end of the finger elastically down on the cutters.

2. The combination with the finger-bar and cutters of mowers, reapers and the like, of a spring-clip comprising a box-like cap or housing, a rigid finger loosely fulcrumed on the finger-bar and projecting beyond the cap over the cutters, and a spring under the cap for holding the front end of the finger elastically down on the cutters.

3. The combination with the finger-bar and cutters of mowers, reapers and the like, of a spring-clip comprising a box-like cap or housing having a turned-down lip or edge at its front side, a finger fulcrumed on the said turned-down edge, and a spring under the cap behind the fulcrum pressing upward against the rear end of the finger and holding its front end down on the cutters.

4. The combination with the finger-bar and cutters of mowers, reapers and the like, of a spring-clip comprising a box-like cap or housing g , open at its front side, and having the turned-down lip or edge l' , and the ears or projections h^2 at the sides thereof, a finger f having a transverse depression j coöperating with the turned-down edge l' of the cap, and a spring k' reacting against the under side of the rear end of the clip-finger to hold its front end down on the cutters.

In testimony whereof I affix my signature in presence of two witnesses.

JOHN W. PRIDMORE.
